UNITED STATES PATENT OFFICE.

ALEXANDER JAMES McCALLUM, OF LITTLE FALLS, NEW YORK.

HOSE OR SOCK.

Application filed August 5, 1925. Serial No. 48,319.

This invention relates to leg coverings or hose, and more particularly to half hose which do not cover the knee, such as socks for men's wear, the upper end portions of which are of a construction or formation such as to snugly fit the leg and make the socks self-supporting, thereby avoiding the necessity for any garters or separate hose-supporters such as are necessary with socks or half hose as ordinarily made.

Various formations and constructions have been made or proposed for socks, for the purpose of making them self supporting, i. e., for holding them in the intended position on the leg without the necessity for independent or additional garters or supporters, but these prior constructions have not properly accomplished the intended purpose, or are impractical or objectionable for one reason or another. It has been proposed, for example, in hose made from so called "dead" yarns, such as cotton, lisle, silk or other vegetable yarns commonly employed in the manufacture of hose, and which are relatively inelastic, to make the upper portion of the leg of the hose with woolen or other more elastic threads interwoven or alternately woven with the "dead" threads, so that the upper portion of the hose is composed in part of both the relatively elastic and relatively inelastic or "dead" yarns or threads. This construction does not at all accomplish the purpose of the present invention for the reason that the interwoven, relatively inelastic or "dead" threads prevent the woolen or elastic threads from acting in the manner that they would if worsted or woolen yarn or thread alone were employed for the upper portion of the hose. In other words, the upper ends of the hose made with the interwoven elastic and "dead" yarns are not elastic in the sense that all woolen material is. Furthermore, the wool or elastic yarns and the "dead" yarns are affected differently by laundering and age, the one tending to change form or condition more than the other, so that this construction would not prove satisfactory after repeated washings and wear of the hose. It has also been proposed to interweave or incorporate narrow bands or strips of rubber in the upper portion of the hose to give them the required elasticity to be self-sustaining, but the rubber soon loses its elasticity and fails to act as intended. Hose or socks provided at their upper ends with adjustable

fasteners or devices for contracting the sock about the leg above the calf have also been proposed, but such constructions are not comfortable and add to the expense of the 60 hose and to the difficulty of laundering. Still another suggestion is the provision of a garter enclosed or hidden in the upper end of the hose, and which must be removed to wash the hose.

The object of my invention is to overcome the objections and insufficiencies in the prior constructions and suggestions and produce a practical and desirable sock or hose which will fit and grip the leg over the calf so as 70 to hold the hose or sock smoothly and perfectly in position without the use of any separate, independent or additional garter or supporter, which will be comfortable and will retain its shape, and act as intended indefinitely, and which nevertheless will be 75 relatively inexpensive to manufacture, neat in appearance, and can be laundered the same as ordinary hose which are not self-supporting.

In the accompanying drawings:

Fig. 1 is a side elevation of a half hose or sock for men's wear embodying my invention.

Fig. 2 is a side view showing the leg of 85 the hose in place on a leg.

Fig. 3 is a rear view of the same.

Fig. 4 is a side view on a larger scale of the upper portion of the sock, indicating by broken lines the tapering piece which is removed to reduce the upper end.

Except for the upper end portion or cuff, the hose or sock shown in the drawing as an embodiment of my invention, can be knitted or woven in the manner and from 95 the materials commonly employed in the manufacture of hose or stockings, that is to say, the foot and the main portion of the leg of the sock, with the exception of the upper or cuff portion, can be made as usual, 100 from cotton, lisle, silk or other yarns commonly employed in the manufacture of hose. The upper end portion or cuff 10 of the hose or sock, however, is knitted entirely of pure worsted yarn or thread, this cuff or upper 105 portion being preferably about four inches in depth and being formed on the upper end of the portion 11 of the leg, which is made of the cotton, lisle, silk or other "dead" 110 yarn by substituting the worsted yarn or thread in place of the "dead" yarn or thread, so that the cuff or upper end por-

tion forms an integral knitted or woven continuation of the main leg portion 11 of the sock or hose. Preferably, the cuff or upper end portion 10 is made two ply or 5 of a larger gage yarn or thread than the main leg portion 11 of the sock. In addition, the cuff or upper end portion 10 of the sock is fashioned so that the upper end of the completed sock tapers or gradually 10 decreases in diameter somewhat towards its upper extremity so as to fit snugly and smoothly over the calf of the leg of the wearer and grip the leg over or above the calf. For this purpose, in the case of socks 15 or hose having a tubular leg which has been knitted straight, as by the usual hose knitting machine, a tapering or wedge-shaped piece with curved side edges, indicated at 12 in Fig. 4, is cut out of the rear upper portion 20 of the hose or sock, extending from the upper end of the sock preferably to a point somewhat below the worsted cuff 10, and decreasing in width downwardly to nothing at its lower end. After this piece has been 25 cut out, the edges of the tapering opening left are joined by stitching, or in any suitable way, thus forming a longitudinal seam 13 at the rear of the sock extending from the upper end thereof, partway down the leg preferably below the cuff 10. The upper edge of the worsted cuff or upper end portion 10 of the sock is also preferably hemmed as shown at 14.

The cuff or upper end portion of the sock 30 fashioned as described will conform perfectly to and snugly fit over the calf of the leg and grip the contracted portion of the leg below the knee. The sock will be thereby supported on the leg so as to smoothly 35 fit throughout and not sag or wrinkle at any portion, and the sock will be entirely self-supporting, requiring no other means or device for holding it up properly on the leg, in fact the sock will be held more perfectly 40 on the leg than is possible by means of the garters commonly employed.

In the case of socks or hose in which the whole leg or sock is made entirely from worsted or analogous yarn having the

requisite inherent elasticity, the upper end 50 portion corresponding to the cuff or portion 10 in the sock above described does not have to be made from material different from the remainder of the leg, but the upper end portion will be fashioned in the manner described to cause it to properly fit and grip 55 over the calf of the leg of the wearer.

I claim as my invention:

1. A sock or hose, the upper end portion of which is knitted and composed wholly of 60 elastic woolen yarn and has a seam joining downwardly converging edges of said upper end portion so that the upper end portion of the leg is elastic and decreases in diameter upwardly, said sock being of a 65 length adapting said decreasing upper end portion to snugly fit the lower leg of the wearer above the largest part of the calf and hold the sock or hose up in position on the leg.

2. A sock or hose in which the upper end portion of the leg is knitted and composed wholly of woolen yarn and the adjoining portion of the leg is composed of less elastic material, and the upper portion of said sock 75 or hose having a seam joining downwardly converging edges of said upper end portion so that the upper end portion of the leg is elastic and decreases in diameter upwardly, said sock being of a length adapting said 80 upper end portion to fit snugly on the contracting upper portion of the calf of the leg of the wearer and hold the sock or hose up in position on the leg.

3. A sock or hose in which the upper end 85 portion of the leg is composed wholly of elastic woolen yarn and has a seam connecting downwardly converging edges of said upper end portion so that the upper end portion of the leg is elastic and decreases in 90 diameter upwardly, said sock being of a length adapting said upper end portion to snugly fit the lower leg of the wearer above the largest part of the calf and hold the sock or hose up in position on the leg, said 95 elastic upper end portion of the sock or hose also having a hem at its upper end.

ALEXANDER JAMES McCALLUM.
